UNITED STATES PATENT OFFICE.

JOSEPH CLIFFORD DANDO, OF PHILADELPHIA, PENNSYLVANIA, ASSIGNOR TO THE DANDO PRINTING AND PUBLISHING COMPANY, A CORPORATION OF PENNSYLVANIA.

DESIGN FOR A FILING-CABINET.

44,748.

Specification for Design.

Patented Oct. 21, 1913.

Application filed July 18, 1912. Serial No. 710,262. Term of patent 14 years.

To all whom it may concern:

Be it known that I, JOSEPH CLIFFORD DANDO, a citizen of the United States, residing at Philadelphia, in the county of Philadelphia and State of Pennsylvania, have invented a new, original, and ornamental Design for Filing-Cabinets, of which the following is a specification, reference being had to the accompanying drawing, forming part thereof.

The figure is a perspective view of a filing cabinet, showing my new design.

I claim:

The ornamental design for a filing cabinet, as shown.

JOSEPH CLIFFORD DANDO.
